UNITED STATES PATENT OFFICE.

FRANK KNOBELOCH, OF DAYTON, OHIO, ASSIGNOR TO THE KINNARD MANUFACTURING COMPANY, OF SAME PLACE.

BOX.

SPECIFICATION forming part of Letters Patent No. 634,645, dated October 10, 1899.

Application filed February 18, 1899. Serial No. 706,042. (No model.)

To all whom it may concern:

Be it known that I, FRANK KNOBELOCH, a citizen of the United States, and a resident of Dayton, in the county of Montgomery and State of Ohio, have invented certain new and useful Improvements in Boxes, of which the following is a full, clear, and exact description, reference being had to the accompanying drawings, forming part of this specification.

My invention relates to an improvement in boxes or packages designed more particularly for shipping perishable articles—such as lamp-chimneys, lamp-globes, lamps, &c.—which are now packed in straw or excelsior. To pack those articles in the usual way is expensive, is attended with much risk, and makes a heavy awkward package, whereas by means of my improvement they are packed for shipment with safety, economy, and in a light convenient package.

In the drawings, Figure 1 is a plan view of the blank cut and scored in the proper manner. Fig. 2 is a perspective view of the box partially folded. Fig. 3 is a top plan view of the box completely folded. Fig. 4 is a horizontal cross-section of the box, showing a lamp-chimney in position.

The blank is cut from a rectangular piece of cardboard or other suitable material, the only waste being in the small portions cut out in forming the locks. Said blank is shown in Fig. 1 cut and scored in the proper manner. The scores *a a a a* and *b b* determine the width and length, respectively, of the sides *A A' A'*. The blank has on one side a flap *J*, which is used in gluing the sides together. The sides are provided at each end with flaps *B B' C C'* and *B' B' C' C'*. These flaps are connected by the portions *D D D* and *D' D' D'*, said portions being determined by the scores *d d d*, &c., *d' d' d'*, &c. The scores *a a a* are prolonged over this portion *D*, so that they may be folded upon themselves. The length of the scores *d* are determined by the distance on the diagonal between the corners of the box and the outer periphery of the lamp-chimney or other article to be shipped, as seen in Fig. 4. The flaps *B B* and *B' B'* are provided with slots *g g* and *g' g'* and the flaps *C C* and *C' C'* with the laterally-extending tongues

E E E E and *E' E' E' E'*, adapted to fit within said slots.

In folding the box the sides are folded at right angles along the scores *a a a a* and the flap *J* is glued or otherwise fastened to the edge of the side *A'*, as shown in Fig. 2. The portions *D D D D* are then folded upon themselves inwardly in a bellows fold along the scores *a a a a*. The flaps *B B* are folded along the scores *b b*, the one flap upon the other, and then the flaps *C C* are folded along the scores *b b*, the two flaps *C C* overlapping each other by the width of the tongues *E E*. These tongues are then slipped into the slots *g g*, thus locking all the flaps together.

A piece of tin or other thin material may be used to slip into the bellows folds and force them into a position at right angles to the top or bottom of the box, and thus insure their bearing against the chimney or other article to be shipped, as shown in Fig. 4.

Instead of the flaps being connected by the bellows folds *D* these folds may be split along the score *a*, thus leaving the flaps separate, the object being simply to have a part that will fold bodily inward and brace against the article to be packed. The bellows fold, however, is the preferable form, as it makes a stiffer brace.

In packing the chimney one end of the box may be closed first, then the chimney put in from the other end and that end closed.

Having thus described my invention, what I wish to claim by Letters Patent is—

1. A box for shipping fragile articles made from a blank having sides, and end flaps integral with said sides, said flaps being connected by bellows folds adapted to fold bodily inward and brace against the article to be packed, said flaps being locked in any convenient manner, substantially as and for the purpose described.

2. A box for shipping fragile articles made from a blank having sides and end flaps integral with said sides, said flaps being provided with parts adapted to fold bodily inward and brace against the article to be packed and hold it in position, said flaps being locked together in any convenient manner substantially as and for the purpose described.

3. In a box for shipping fragile articles made from a blank having sides and end flaps being connected by bellows folds, adapted to fold bodily inward and brace against the article to be packed, two alternate flaps having slots, and the other two laterally-extending tongues adapted to fit within said slots, and thus lock the flap together, substantially as and for the purpose described.
4. A box made from a blank having sides and end flaps integral with said sides, said

flaps being connected by bellows folds adapted to support the article to be packed and two alternate flaps having slots and the other two laterally-extending tongues adapted to fit within said slots and thus lock the flaps together, substantially as described.

FRANK KNOBELOCH.
